UNITED STATES PATENT OFFICE

105,605

DESIGN FOR A DRESS ENSEMBLE

Margaret Michelson, New York, N. Y.

Application June 30, 1937, Serial No. 70,118

Term of patent 3½ years

To all whom it may concern:

Be it known that I, Margaret Michelson, a citizen of the United States of America, residing in Manhattan, county of New York, and State of New York, have invented a new, original, and ornamental Design for a Dress Ensemble, of which the following is a specification, reference being had to the accompanying drawing, forming part thereof, wherein,

The tucks on the front bodice portion of the dress unit are graduated in size to give a sunburst appearance.

I claim:

The ornamental design for a dress ensemble, substantially as shown and described.

MARGARET MICHELSON.
